Assistant Examiner—Ricky Pham

(57) **CLAIM**

The ornamental design for an automatic baby formula maker, as shown and described.

DESCRIPTION

FIG. 1 is a front elevation view of an automatic baby formula maker showing my new design.

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is perspective view of my invention.

The broken lines showing the baby bottles in FIGS. 1-3 is for illustrative purposes only and form no part of the claimed design.
